ALTERNATING-CURRENT SIGNAL
TRANSMITTING SYSTEM

Henri Gardère, Paris, France, assignor to Compagnie Générale d'Électricité, Paris, France, a corporation of France

Application May 20, 1946, Serial No. 670,891
In France May 7, 1945

Section 1, Public Law 690, August 8, 1946
Patent expires May 7, 1965

4 Claims. (Cl. 178—66)

1

The present invention relates to the transmission of telegraph code signals and has for its object to provide a frequency change signal transmitting system of the so-called double current and phase modulation type, characterised by the fact that: at the transmitting end the direct current signals of both positive and negative types are converted into two types of alternating current signals having a phase difference of between 0 and π ; at the receiving end the carrier current is reconstituted from the signals with a constant phase, and by means of said carrier current the alternating current signals are demodulated (i. e. reconverted into direct current) without any uncertainty as to their correct polarity and having durations which are independent of the amplitude of the alternating current signals. In a "double current" alternating current system, there is transmission of alternating current during both the spacing keying intervals and the marking keying intervals.

The advantages of such double current telesignal systems are known, such advantages being due to the fact that the signals reconstituted at the receiving end are independent of the amplitude of the changed frequency current signals changed at the input of the receiver. The known double current telesignal system operating by means of reversals of the phase of the alternating current in synchronism with the reversals separating the direct current signals has this advantage, but does not reliably give the signals with their correct polarity at the beginning of a communication. The receiver cannot determine the polarity of the direct current signals which correspond to the alternating current signals received, since the successive signals comprise reversals which indicate nothing regarding the absolute value of the polarity of the signals. Only the relative polarity of the signals is known, i. e. that a signal is of opposite polarity to the previous or to the following signal.

From this it is apparent that in these known double current systems it is only possible to determine the absolute polarity by conventions relating to the actual signal code. Thus electro-mechanical analysers have been constructed which enable the exact absolute polarity to be recognised by utilising peculiarities of the signal code used. But in addition to the fact that this device complicates reception, it is only applicable to the one signal system, that is, a system using a determined type of signalling such as Baudot, Wheatstone, Hughes, or start-stop.

It is due to this difficulty that double current

transmission involving frequency change (and carrier current) have not heretofore been as generally used as should have been warranted by their property of independence of amplitude at the receiving end. Single current communications remain the most generally used despite their distortion which is function of the reception level and, in order to minimize this serious defect, there is at present a tendency to allot to them a wider frequency band, which makes them less economical in spectrum requirement.

Fig. 1 shows one form of receiving circuit for receiving doubly phased modulated carrier signal currents and converting them into direct current signals, using a balanced demodulator, the polarity of the initial direct current element corresponding to the polarity of the initial element of the signal applied to the transmitter;

Fig. 2 shows the vector relations in the receiving circuit of Fig. 1, when the first element of the received signal is a spacing element;

Fig. 3 shows the vector relations in the receiving circuit of Fig. 1, when the first element of the received signal is a marking element;

Fig. 4 shows a modified form of circuit using a single demodulator for accomplishing the same result as the arrangement of Fig. 1;

Fig. 5 shows the vector relations in the receiving circuit of Fig. 4, when the first element of the received signal is a spacing element; and

Fig. 6 shows the vector relations in the receiving circuit of Fig. 4 when the first element of the received signal is a marking element.

In the system according to the present invention, the signal changer at the transmission end produces alternating current signals which do not differ by a change of sign, but by a change of phase which is smaller than π in absolute value. For instance, the alternating current corresponding to a negative direct current marking signal as produced by the key, has a phase advance of an angle ϕ which is smaller than π with respect to the alternating current corresponding to a space signal. Obviously it would be possible to make the reverse convention, viz. a mark signal having a phase lag of ϕ with respect to the space signal.

In the known double current system of the prior art referred to above, operating by reversals of the alternating current, the direct current signals which are reconstituted at the receiving end are not dependent on the amplitude at the input of the demodulating receiving system, because the duration of such reconstituted signals is equal

2

to the time between the reversals of the alternating current signals. In the system according to the present invention, the same advantage is obtained, because the duration of the reconstituted signals is equal to the time between the changes of phase of the alternating current signals and is not dependent on their amplitude. But whereas in the prior art double current system operating by reversals, the absolute polarity of the signals cannot be determined, in the system according to the present invention, it is clear, as soon as the second signal appears in the receiving demodulator, whether said signal is a mark signal or a space signal (i. e. negative or positive), according to whether said signal has an advance or a lag of the phase angle ϕ in accordance with the convention hereinbefore agreed. Thus the reconstituted signals have the same polarity as at the transmitting end, with means independent of the code of the signal or telegraph system used.

The change of phase at the transmitting end can be obtained, according to the present invention, in the following manner: two sources of alternating current of the same frequency and with a phase difference equal to ϕ alternately transmit their current to the line through one or a plurality of dynamic or static, electro-mechanical or electronic relays, which are controlled by the direct current signals of the signal or telegraph apparatus. In accordance with the convention hereinbefore agreed (alternating current having a phase advance of ϕ for a direct current mark or negative signal with respect to the alternating current for a spacing signal element as produced by the key), the mark signal or negative direct current operates the relay or relays which connect to the line the source of alternating current having such a phase advance of ϕ . Said source is replaced by the other alternating current source when the relay or relays are operated by a direct current spacing or positive signal.

Obviously the two sources could be replaced by a single source provided with two parallel leads connected to one or two dephasing devices producing at the output of said leads currents which are ϕ out of phase, and instead of connections being made to the two sources, the connections are made to the two parallel leads.

Another example of frequency change means producing signals which are out of phase by ϕ consists in permanently connecting the alternating current source to the line and inserting a dephasing device between the source and the line by means of relays controlled by the direct current signals. It is thus possible to obtain, applying one of the two (positive or negative) types of direct current signals, the phase difference of ϕ in question.

Another example, according to the present invention, of frequency change at the transmitting end, that is, the transformation of D. C. signals (zero frequency) into A. C. signals of the carrier frequency, consists in using a known frequency changer of the double current type as employed in the prior art operating by reversals of the alternating current, and in transmitting to the line, in addition to the double current alternating current signals produced by reversals, an auxiliary current which has a

phase advance with respect to one, and a

$$\frac{\pi}{2}$$

phase lag with respect to the other, of the two alternating current signals. If it is desired to have a phase lag of ϕ between the two resulting signals, A being the amplitude of the signals at the output terminals of the frequency changer, and a the amplitude of the auxiliary current, the following equation must be satisfied:

$$\frac{A}{a} = \tan \frac{\phi}{2}$$

The auxiliary current must have an advance with respect to the space signal current, if adhering to the aforesaid assumed convention of a mark signal current having an advance of phase with respect to the space signal current. Another example consists in using a variable phase source of alternating current and controlling the phase by means of a relay controlled by the direct current keying signals.

The signals thus obtained from the transmitter reach the input of the demodulating device at the receiving end in the form of alternating current. According to the aforesaid convention, it is assumed that the alternating current corresponding to a mark signal has a phase advance of ϕ with respect to the alternating current of the same frequency corresponding to a space signal. It is obvious that the converse convention could be made, but in order to simplify the explanation the first mentioned convention will be adhered to throughout the remainder of the present specification.

Moreover, in order to simplify further, it will be assumed that the phase difference ϕ has the value

$$\frac{\pi}{2}$$

On this basis, the members at the receiving end will, in general, be simpler, but the description would remain true with any angle ϕ smaller than π conditionally on the members producing the dephasing being modified accordingly. However, although the adoption of ϕ in no way affects the principle of the system provided that this angle is between 0 and π , the construction of the system will be all the easier according as the phase difference approaches closer to

$$\frac{\pi}{2}$$

Fig. 1 shows the diagram of a system according to the invention adapted to convert alternating current signals into direct current signals at the receiving end; the input terminals to which the alternating current signals "is" are fed are located at e. f is a preliminary filter for the signals which is particularly intended to separate the signals of various communications on several different frequencies, in the case of multiplex channels as known. For the purposes of the transmission, said preliminary filter passes a band of at least

$$\frac{1}{t}$$

cycles, t being the elementary time, i. e. the duration of the shortest possible interval; the maximum band width is determined by the filtering requirements or by the desirability of eliminating or attenuating parasites. The filter may be

simple, this being an advantage involved in double current alternating current communication, as the filtering can be completed after demodulation, simply by a low-pass filter.

At the output terminals of the fs filter, d_1 is a parallel lead through which the signal current can reach either the input terminals of the signal amplifier as , or the input terminals of the blocking devices br , bt . These blocking devices are units which only allow signal current from d_1 to pass from the input terminals to the output terminals (from the left-hand terminals to the right-hand terminals) when they are supplied with direct current at their control terminals (upper terminals). Such blocking units are well known in weak current technique and may consist of a simple network of rectifiers.

The output terminals of the blocking devices br and bt are in parallel, i. e. connected to one another. But whereas the connecting leads are directly connected to the output terminals of br , the output terminals of bt are connected, ahead of the leads, to a dephasing device st which produces a lag of

$$\frac{\pi}{2}$$

in the currents that pass through it. The output leads are connected to the input terminals of the carrier current band pass filter fp . Said filter, which is centered on the carrier frequency, should pass a band width of less than

$$\frac{2}{t}$$

t being the duration of the elementary signal. But more often it will be an advantage to have as reduced a band width as possible compatible with the stability of the elements and of the carrier frequency. The output of the carrier filter fp is fed direct to an amplifier ar for the space signal carrier current and, through a dephasing device so producing a lag of

$$\frac{\pi}{2}$$

to an amplifier at for the mark signal carrier current.

The aforesaid signal amplifier as is connected to the input terminals of two demodulators in parallel, the space signal current demodulator mr and the mark signal current demodulator mt . The output terminals of the demodulators (right-hand terminals) are also connected in parallel.

The control terminals (upper terminals) of the demodulators mr and mt are respectively connected to the output terminals of the amplifiers ar and at . The demodulators are units of the known balanced type called "carrier current suppressors." They are such that if a current $i(t)$ is applied to the input terminals and a current $I(t)$ to the control terminals, they produce at the output terminals a current of the form $a.i(t).I(t)$, a being a constant. It ensues from this property, as is well known, that if currents of the same frequency but out of phase by an angle ψ are applied to the input and to the control terminals, a direct current proportional to $\cos \psi$ is obtained at the output terminals which is, therefore, independent of the amplitude of the input.

The output terminals of the demodulators are connected in parallel and are connected to a low-pass filter fc , the cut-off frequency of which is at least equal to $\frac{1}{2}t$, t being the duration of

the shortest possible signal. A control circuit d_2 is connected across the control terminals of the blocking devices br and bt through valves or rectifiers rr and rt which only allow current to pass in the direction of the arrows that represent them. This control circuit d_2 is connected in series in one of the leads connecting low pass filter fc to the output terminals of demodulators mr and mt .

Fig. 1 enables an explanation to be given of the operation of the system illustrated therein by way of a non-limitative example, according to the present invention, of the receiving portion which converts the alternating current signals identical to those transmitted.

Two cases may arise: either the first signal is a space signal, or the first signal is a mark signal.

1. *First case.*—Assume that when the transmission is started the first alternating current signal that reaches the input e of the receiver of Fig. 1 is a space signal current. It passes through the band-pass filter fs —which may be a simple one (the system enabling the signals which have been re-converted into direct current signals to be filtered by a simple low-pass filter)—then the current reaches the parallel connection d_1 . One portion of the current is amplified in the signal amplifier as and is fed to the input terminals of the two demodulators in parallel mr and mt (left-hand terminals of the demodulators). The other portion of the signal which is shunted at d_1 passes through the blocking device br .

It was stated hereinbefore that the blocking devices br and bt only allow current to pass between the input and output terminals when their control terminals are supplied with direct current, therefore if the blocking of br and bt is complete, the current is a zero current, save the initial signal current; in the initial state br has to be blocked.

In order that the signal current shall be able to pass through br , the same is so designed that in the blocked state it allows a current to pass which is small compared with the current that would pass with br open. The current having passed through br , flows into the carrier current filter fp . At the output of the carrier current filter fp , the signal current which is still of the same phase (space) is shunted towards the input terminals of two amplifiers: directly across the input terminals of the space signal current amplifier ar and, through a dephasing device sp which throws it

$$\frac{\pi}{2}$$

out of phase, across the input terminals of the mark signal carrier current amplifier at .

The amplifier ar therefore produces at its output terminals a current of the same phase as the initial current and the amplifier at a current having a phase lag of

$$\frac{\pi}{2}$$

These two amplifiers respectively supply the "control" or "carrier current" terminals of the two demodulators mr and mt which, moreover, as hereinbefore stated, are fed in parallel through their input terminals by the signal current amplified by signal amplifier as . At this moment, the demodulator mr which is fed through its input terminals and through its "carrier current" control terminals with currents which are in phase, supplies a direct current across its output terminals; the connections are in a direction such

that said direct current flows through the low-pass filter fc and the output terminals s in the direction of the arrow which is assumed to be the positive direction. The demodulator mt which is fed with currents which are

$$\frac{\pi}{2}$$

out of phase supplies zero current.

Before reaching the output terminals, the current from the two outputs connected in parallel of the two demodulators is directed at d_2 towards the control terminals of the two blocking devices br and bt ; it operates one or the other of said blocking devices by passing through one or the other according to its direction through the valves or rectifiers rr and rt which are unilaterally conducting. In the present case the direction of the current is such (direction of the arrow, space signal or positive current) that it passes through the valve rr and the blocking device br which is thus made open, whereas the blocking device bt , through which no current passes owing to the direction of the valve rt , remains blocked. The blocking device br therefore allows the current derived at d_1 to pass freely towards the carrier band pass filter fp , which only increases the weak current that it allowed to pass at the outset. This also increases the currents in the various circuits with their polarity and their phase as they were hereinbefore described.

When the received initial space signal applied at e is replaced by a mark signal, the flow of this current involves (according to the assumed convention) a phase advance of

$$\frac{\pi}{2}$$

in the alternating current forming the signals. Owing to the high time constant of the carrier current filter fp , the phase and the amplitude of the current at the output terminals of said filter fp can only change with a certain delay, so that the carrier currents amplified by amplifiers ar and at have not changed when the mark signal, which has a phase advance of

$$\frac{\pi}{2}$$

is applied to the input terminals of its demodulators.

The demodulator ar which produced a positive current, now at this instant produces no current since the current at the input terminals and the carrier current are

$$\frac{\pi}{2}$$

out of phase. The demodulator mt , which produced no current, is still supplied with a carrier current which has a phase lag of

$$\frac{\pi}{2}$$

and now has at its input terminals a signal current which has a phase advance of

$$\frac{\pi}{2}$$

(mark signal), the signal current and the carrier current for the demodulator mt are therefore in phase opposition and it produces at its output terminals a negative demodulated direct current.

Owing to the change of polarity of the demodulated direct current, said current cannot pass through the blocking device br which is blocked,

but it passes through the blocking device bt which owing to this fact is open, i. e. has only a small attenuating effect on the signal current flowing from the parallel leads d_1 . Instead of, as in the previous case (space signal current), the current (marking signal) passing through the blocking device br and reaching the carrier current filter fp , it now passes through the blocking device bt and reaches the filter fp through the dephasing device st which imparts to it a phase lag of

$$\frac{\pi}{2}$$

Now, in the present case the current representing a mark signal which, with respect to the previous signal, has a

$$\frac{\pi}{2}$$

phase advance, next after passing through the dephasing device st , gets a

$$\frac{\pi}{2}$$

phase lag, thus undergoes two successive equal and opposite changes of phase, the overall effect of which is nil. Therefore the current at the input terminals of the filter fp does not undergo a change of phase.

At the instant when the space signal current changes to mark signal current, there may of course be a short instant during which the current at the input terminals of the filter fp changes its amplitude or its phase, but such instant is short compared to the time constant of the filter, so that if the phase remains constant at the input terminals of the filter fp for greater part of the time, it may be considered to be absolutely constant at the output terminals of the filter for the purposes of demodulation.

The analysis of the operation gives, for the time constant of the filter fp , a value at least equal to one half of the duration of an elementary signal (i. e. of the shortest possible signal) for the current at the output terminals to remain sufficiently constant. Thus the above explanation shows that if the first signal that arrives is a space signal, the system described produces a positive direct current for a space signal and a negative direct current for a mark signal. Before reaching the output terminals s , the signals which have been re-converted into direct current pass through the low-pass filter fc which eliminates the unwanted demodulation components and the components of adjacent signaling channels which might remain.

2. Second case.—In the other contingency when the first signal that arrives is a mark signal, it is obvious that the system described cannot detect its phase in an absolute manner. For this first signal the receiver produces, as in the first case, a positive direct current which is consequently incorrect. The system operates as previously described, for any initial signal whatever be the phase of such signal. The operation changes as soon as the second signal appears, which will now be a space signal. The arrival of this second signal produces (change from mark to space) a phase lag of

$$\frac{\pi}{2}$$

During the first signal (as in the first case) the demodulator mr , whose input terminals were supplied with the signal current and the "control" terminals with a carrier current of the same phase, produced a positive current at the output terminals, whereas the demodulator mt , which

was controlled by a carrier current having a phase lag of

$$\frac{\pi}{2}$$

produced no current. The positive current at the output terminals of the modulator *mr* opened the blocking device *br*.

At the beginning of the second signal which has a phase lag of

$$\frac{\pi}{2}$$

with respect to the previous mark signal, the demodulator *mr* produces no demodulated current, and the demodulator *mt* (still supplied with carrier current having a phase lag of

$$\frac{\pi}{2}$$

owing to the effect of the time constant), the carrier current of which is in phase, produces a positive current. This positive demodulated current causes the blocking device *br* to remain open. Thus in this second case, when the second signal arrives, the demodulated current does not change its polarity and the blocking device *br* remains open, so that the current of the second (space) signal remains applied to the input terminals of the carrier current filter *fp* with its own phase, i. e. with a phase lag of

$$\frac{\pi}{2}$$

with respect to the first signal.

At the output terminals of the carrier filter *fp* and throughout the duration of the second signal, the phase of the carrier current gradually changes, according to the time constant, from the phase of the first signal to the phase of the second. Simultaneously, the two carrier currents which supply modulators *mr* and *mt*, undergo the same change of phase (backward displacement of

$$\frac{\pi}{2}$$

and the current *imr* demodulated by *mr* gradually changes from 0 to its normal positive value, whereas the current *imt* demodulated by *mt* gradually changes from its positive value to 0.

Throughout all this change, the two demodulators *mr* and *mt* as a whole, produce a positive total current and the blocking device *br* remains open. After the change of phase of the carrier currents *imr* and *imt*, the space signal is demodulated by the demodulator *mr*, whereas *mt* produces no current. The system has thus returned to the state in which it was in the first case when a first space signal was being demodulated. Thus, apart from the first signal which may be incorrectly received if it is a mark signal, the system produces a positive current for the space signals and a negative current for the mark signals.

In order to give greater clarity to the description of the foregoing operations, of the circuit of Fig. 1, there is shown for the first case when the first signal received is a spacing signal, in Fig. 2: at *a* the vectors *isr* representing the space signals and *ist* with an advance of

$$\frac{\pi}{2}$$

representing the mark signals; at *b* and at *c* the signals and currents illustrating the first case of operation. At *b*, *isr* represents the initial space signal applied to the system, *ipr* the carrier cur-

rent produced by the first signal and fed to the demodulator *mr*, *ipt* which has a phase lag of

$$\frac{\pi}{2}$$

representing the carrier current fed to the demodulator *mt*, *imr* is the positive current produced from *isr* and *ipr* in phase in the demodulator *mr* and *imt* is the zero current demodulated from *isr* and *ipt* in quadrature in the demodulator *mt*.

At *c*, *ist* represents the mark signal following the initial signal, *ipr* and *ipt* the carrier currents which remain permanently owing to the effect of the large time constant filter *fp* and of the opening of the blocking device *bt* instead of *br*, *imr* is the zero current produced from *ist* and *ipr* in phase quadrature in *mr*, and *imt* is the negative current produced from *ist* and *ipt* in phase opposition.

In Fig. 3 have been shown for the circuit of Fig. 1 the signals and currents illustrating the second case of operation when the first signal that arrives is a marking signal. At *d* in Fig. 3, *ist* is the initial mark signal, *ipr* and *ipt* the carrier currents produced thereby and having a

$$\frac{\pi}{2}$$

phase advance with respect to their normal position, *imr* the positive current produced from *ist* and *ipr* in phase in *mr*, and *imt* the zero current produced from *ist* and *ipt* in phase quadrature in *mt*. At instant *f* (Fig. 3), *isr* is the space signal current that follows the current of the initial signal, *ipr* and *ipt* the carrier currents which have not yet had the time to change and are identical with those shown at *d* (Fig. 3). *imr* is now zero and *imt* produced from *isr* and *ipt* in phase in *mt* is positive. At instant *g*, *h* and *i* is shown the backward rotation of the carrier currents *ipr* and *ipt* during the space signal *isr* which has a

$$\frac{\pi}{2}$$

phase lag with respect to the previous signal. In the lower row of Fig. 3 are shown the corresponding variations of the demodulated currents produced. *imr* which is zero at instant *f* acquires increasing positive values and *imt* retains positive but decreasing values. At instant *j* is again the space signal *isr*, the carrier currents have reached their normal phase, *imr* is positive and *imt* is zero. The system is in the state shown in Fig. 2 at *d* and is therefore ready to receive correctly the next mark signal.

Fig. 4 shows the diagram of another non-limitative example, according to the present invention, of a system which re-converts at the receiving end the phase modulated alternating current signals into direct current signals. At *e* are the receiver input terminals, *fs* is a pre-filtering filter having the same functions and the same characteristics as in the previous example of Fig. 1, *d* is a parallel connection through which the current of the signals from *fs* can reach, either the input terminals of the signal amplifier *as*, or the input terminals of the blocking devices *br* and *bt* in parallel. Said blocking devices are units comprising rectifier bridges which produce between their input and output terminals (extreme left-hand terminals for the input, extreme right-hand terminals for the output) a small or large decrease of intensity according to whether direct current flowing in one direction or in the

other is fed to their control terminals (mid terminals on both sides.)

Thus blocking devices br and bt produce a negligible decrease when direct current is passing through them in the direction of the arrow (arrow inside the square which represents them). They will produce a large decrease, in other words they will be nearly blocked, when a direct current flowing in the opposite direction is passing through them. In fact, these blocking devices produce the same effects as the blocking devices and their valve in the previous example of Fig. 1. Such blocking devices are likewise known in weak current technique. At the output terminals of the blocking device br is connected a dephasing device sr which imparts to the currents passing through it a phase lag of

$$\frac{\pi}{4}$$

and at the output terminals of the blocking device bt another dephasing device st imparts a phase lag of

$$\frac{3\pi}{4}$$

(still assuming the convention of a mark signal current having a phase advance of

$$\frac{\pi}{2}$$

with respect to the space signal current). Following the two dephasing devices, the circuits fed with the output of the two blocking devices are connected to the input terminals of the band-pass filter fp .

This band pass filter fp which is centered on the carrier frequency has similar characteristics to those of the filter fp of the previous example of Fig. 1. The output terminals of the filter fp are directly connected to the input terminals of the carrier current amplifier ap . The output terminals of the signal amplifier as previously referred to are connected to the input terminals (left-hand terminals) of the demodulator m , the control terminals of the demodulator m (upper terminals) are connected to the output terminals of the amplifier ap . The demodulator m is a unit of the type of those used in the previous example of Fig. 1. The output terminals of the demodulator are connected to a low-pass filter fc having similar characteristics to those of the filter of the same designation in the previous example of Fig. 1. Between the output terminals of the demodulator m and the input terminals of the filter fc , a parallel lead d_2 is connected to the control terminals of the blocking devices br and bt . In the ensuing explanation of the operation of this second modification, reference will be made to Fig. 4 hereinbefore described.

As in the previous example of Fig. 1, two cases have to be considered according to whether at the outset the first signal to reach the receiver is a space signal or a mark signal.

1. *First case.*—The first signal is a space signal. The current of this signal passes through the filter fs , reaches the parallel lead d_1 . One portion of said current is amplified in the signal amplifier as and is fed to the input terminals of the demodulator m . The other portion of the signal which is shunted through d_1 flows along two parallel leads and partly passes through the blocking devices br and bt which, owing to the initial absence of direct current at their control terminals (mid terminals) are neither open nor

blocked. The signal current then passes through the dephasing devices sr and st , reaches the input terminals of the carrier band pass filter fp , passes through same and is then amplified by the carrier current amplifier ap and fed to the control terminals of demodulator m .

The blocking devices br and bt should be so designed that their transmission properties, in the absence of direct control current, allow such currents to pass that at the output terminals of ap and at the control terminals of m , there is a current which differs in phase by less than

$$\frac{\pi}{2}$$

from the initial signal current at the input terminals of the demodulator m .

Thus the demodulator m , to the input and control terminals of which are fed currents that differ in phase by less than

$$\frac{\pi}{2}$$

produces at its output terminals a positive direct current im (direction of the arrow at the output terminals of m). Said direct current, which is diverted at d_2 , passes through the two blocking devices br and bt by way of their control terminals and, owing to its polarity, opens br and blocks bt . The signal current from the shunt lead d_1 which was passing through the blocking devices br and bt now only passes through br , is given a phase lag of

$$\frac{\pi}{4}$$

by the dephasing device sr , passes through fp and, after being amplified by ap , is fed to the control terminals of m . The demodulator m , which now has currents differing in phase by

$$\frac{\pi}{4}$$

fed to its input and control terminals, produces a positive current im at its output terminals. Thus the initial current im will be increased in the same direction so long as the initial space signal current lasts, producing at the output terminals after passing through fc a space signal correctly re-converted into direct current.

When the initial space signal is replaced by a mark signal current, the flow of this current involves (according to the assumed convention) a phase advance of

$$\frac{\pi}{2}$$

Owing to the large time constant of the carrier current filter fp , the phase and the amplitude of the current at the output terminals of said filter can only change after a certain delay, so that the carrier current amplified by amplifier ap and fed to the demodulator m has not changed (still has a phase lag of

$$\frac{\pi}{4}$$

when the mark signal is applied to the input terminals of the demodulator. The mark signal has a phase advance of

$$\frac{\pi}{2}$$

with respect to the initial space signal, the carrier current a phase lag of

$$\frac{\pi}{4}$$

13

This mark signal current and the carrier current are therefore out of phase by:

$$\frac{\pi}{2} + \frac{\pi}{4} = \frac{3\pi}{4}$$

i. e. more than

$$\frac{\pi}{2}$$

and the demodulator will produce a negative current at the output terminals. This negative current through the parallel lead d_2 closes br and opens bt . The mark signal current from d_1 having a phase advance of

$$\frac{\pi}{2}$$

passes through bt , is given a phase lag of

$$\frac{3\pi}{4}$$

by the dephasing device st and reaches fp with a phase lag of

$$\frac{3\pi}{4} - \frac{\pi}{2} = \frac{\pi}{4}$$

Thus the current at the input terminals of the carrier band pass filter fp does not change its phase.

At the instant when the space signal changes into a mark signal, there may possibly be a short instant when the current at the input terminals of fp changes its amplitude or its phase, but this instant is short compared to the time constant of the filter, so that the carrier current may be considered to be of constant amplitude and phase at the output terminals of the filter fp and therefore at the control terminals of the demodulator. The demodulated current im will therefore be negative as long as the mark signal current lasts. The space and mark signals are thus reconstituted with their correct polarity.

2. Second case.—The first signal is a mark signal. It is obvious that at the beginning of a message, that is to say as soon as an alternating current flows at the receiving end, the system cannot indicate the phase of such current, since a current only has a phase relatively to another current or relatively to a definite origin of time. For this first mark signal, the system will therefore behave exactly as in the first case, i. e. it will produce at the output terminals a positive and consequently incorrect current. There will therefore be, at the control terminals of the demodulator m throughout the whole duration of the first signal, as in the previous case, a carrier current which has a phase lag of

$$\frac{\pi}{4}$$

with respect to the signal current. Similarly, the positive demodulated current im will open the blocking device br and close bt . But at the arrival of the second signal (space signal) which now has a phase "lag" of

$$\frac{\pi}{2}$$

with respect to the previous signal, the difference of phase between the carrier and signal currents at the terminals of m changes from

$$\text{minus } \frac{\pi}{4}$$

to

$$\text{plus } \frac{\pi}{4}$$

14

this difference remaining smaller than

$$\frac{\pi}{2}$$

5 so that the demodulated direct current remains positive.

Therefore the blocking device br will again remain open and the signal current at the input terminals of the filter fp will have a phase lag of

$$\frac{\pi}{2}$$

(relatively to what it was during the first signal). The output current of the filter fp , and the current at the output terminals of carrier amplifier ap and at the control terminals of the demodulator m will therefore gradually change its phase according to the time constant of the carrier band pass filter fp . Like the change of phase of the signal, this change will be a lag of

$$\frac{\pi}{2}$$

25 but slower, the phase of the carrier current relatively to the signal current will therefore change from a

$$\frac{\pi}{4}$$

30 advance to a

$$\frac{\pi}{4}$$

lag. It follows that during any change of phase of the carrier, the demodulated direct current will remain positive.

The second signal (space signal) is therefore correctly received and the system is in the conditions of the first case (first signal a space signal) after the reception of the first signal to receive correctly the next mark signal. The filter fc through which the demodulated currents pass before reaching the output terminals, enables the unwanted components of demodulation to be eliminated and also the components of adjacent signal systems on other frequencies, which the filter fs may have allowed to pass.

In order to give greater clarity to the foregoing description of operation of the circuit of Fig. 4, there is shown in Fig. 5, for the first case when the first signal received is a spacing signal, the vectors representing the currents. At k are shown the two vectors isr representing the alternating current space signals and ist with a phase lag of

$$\frac{\pi}{2}$$

representing the mark signals. At l and n are shown the signals and currents illustrating the first case of operation. At l , isr represents the initial space signal, ip the carrier current produced by this first signal having a phase lag of

$$\frac{\pi}{4}$$

65 im is the positive demodulated current produced from isr and ip which are given a phase difference of

$$\frac{\pi}{4}$$

70 in the demodulator m . At n , ist represents the mark signal current, following the initial signal, ip the carrier current which does not un-

dergo a change of phase and therefore has a phase lag of

$$\frac{3\pi}{4}$$

with respect to *ist* owing to the effect of the time constant of the filter *fp*, of the opening of the blocking device *bt* and of the dephasing device *st*. *im* is the negative direct current produced from *ist* and *ip* which are given a phase lag of

$$\frac{3\pi}{4}$$

in the demodulator *m*.

In Fig. 6 have been shown for the circuit of Fig. 4, the signals and currents illustrating the second case of operation when the first signal element received is a marking signal. At *p*, *ist* is the initial mark signal, *ip* the carrier current which results therefrom and has a phase lag of

$$\frac{\pi}{4}$$

as in the first case. *im* is the positive and therefore, incorrect direct current produced from *ist* and *ip* in the demodulator *m*. At instant *q*, *isr* is the space signal following the initial signal and having a phase lag of

$$\frac{\pi}{2}$$

with respect to same, *ip* is the carrier current which has not had time to change, an *im* the demodulated current resulting therefrom and which is always positive. At instants *r*, *u* and *v* can be seen the gradual backward rotation of the vector representing the carrier current *ip* throughout the duration of the signal *isr*. In the bottom row of Fig. 6 is shown the resulting demodulated direct current *im*. It is always positive, at instant *r* it increases, at instant *u* it passes through a maximum value, at instant *v* it decreases. Finally, at instant *x* there is always the space signal *isr*, the carrier current *ip* has reached its normal phase, *im* is positive. The system is in the condition shown in Fig. 5 at *l*, therefore ready to receive correctly the coming mark signal.

It has not been mentioned in the previous examples, but it is an advantage of double current signal systems and of the present invention that it is possible to add to the signal amplifiers as an amplitude and level regulator which is simple and easy to construct owing to the fact that all the signals involve a flow of current. This latter point is in contra-distinction to single current signal systems which have zero current signals, that is, there are intervals when no current is transmitted, between intervals of different lengths when current is transmitted. It is thus possible to make the carrier current constant, i. e. independent of the slow variations of amplitude of the signals, by means of a simple limiter adjusted to its minimum amplitude. Said limiter is preferably located after the filter *fp* or is added to the amplifiers *ar*, at (Fig. 1) or *ap* (Fig. 4).

The system according to the present invention offers the advantage of giving unequivocally the polarity of the re-converted signals whose distortion is practically independent of the strength of reception. The signals are re-converted according to their type in an exact and well-defined direction. This property involves the possibility, without impairing the transmission, of narrowing the frequency band allotted to each

communication down to the requisite theoretical value. Thus the usual single current communications, at the signal speed of 50 bauds, are allotted a frequency band of 80 to 90 cycles with a serious distortion when the strength of reception varies, and owing to this defect there is a tendency to increase this band width to a value exceeding 150 cycles. The system according to the present invention enables the same message to be transmitted, with a frequency band of only 50 cycles per second, therefore in a multiplex system, two or three times more messages to be transmitted, with better quality of reconstitution.

Furthermore, the system according to the present invention offers the advantage, which is common to all double current signal systems, of being less sensitive to parasites; it requires during transmission smaller power than that used for single current signal systems, and thus has less effect on neighbouring communication.

The system according to the present invention is applicable to all signal systems in which it is an advantage to use alternating current rather than direct current signal, in particular in simple or multiplex signal or tele-communication systems, either wired or wireless. The system can be applied equally well whatever be the transmitting medium and agent, for example: wire and electric current, space and Hertzian or light waves, atmosphere and sound waves, and so forth, provided that at the transmitting end there is conversion of the electric current of the signals according to the present invention into the agent utilized, and the reverse conversion at the receiving end. In particular, in communications by means of Hertzian waves, the systems described is to a great extent insensitive to fading.

I claim:

1. In a receiver for receiving and reconvert-
ing into direct current signal elements of suc-
cessively opposite polarity, a transmitted alter-
nating current signal consisting of successive
short trains of two alternating currents of the
same frequency but having a substantial deter-
mined phase difference *W* which is substantially
less than π , receiving terminals for receiving said
trains of the so determined different phase, a
carrier current suppressing balanced demodu-
lator unit having input terminals and output
terminals and control terminals, said input ter-
minals of said demodulator unit being connected
to said receiving terminals, a pair of blocking
devices having substantial conducting asymmetry
and each having input terminals and output ter-
minals and control terminals and each being
adapted to pass a relatively large current from its
input terminals to its output terminals when di-
rect current of a particular characteristic is ap-
plied to its control terminals and to pass only a
relatively small current from its input terminals
to its output terminals when its control ter-
minals are not so energized, a carrier band pass
filter of relatively large time constant, a connec-
tion between the input of said carrier filter and
the output terminals of said blocking devices,
said connection comprising dephasing means
for dephasing the output of one of said block-
ing devices relative to the output of the
other blocking device by a substantial angle
which is substantially less than π and equal to
said determined phase difference *W* of said two
alternating currents applied to said receiving
terminals, the output of said carrier filter being
connected to the control terminals of said de-
modulator unit, direct current output connections

for said receiver connected to the output terminals of said demodulator unit, and control connections from the output terminals of said demodulator unit to the control terminals of said blocking devices, said control connections and said blocking devices comprising means whereby one and only one of said blocking devices at a time is selectively unblocked to pass a relatively large current according to the polarity of the direct current output of said demodulator unit, whereby the output of said demodulator unit consists of successive direct current signal elements of both polarities as uniquely determined by the phase of the received alternating current signal trains and whereby the phase of the currents applied to the input of said carrier filter is substantially constant and the amplitude of said output is independent of the amplitude of said transmitted alternating current signal trains.

2. In a receiver for receiving and reconverting into direct current signal elements of successively opposite polarity a transmitted alternating current signal consisting of successive short trains of two alternating currents of the same frequency but having a substantial determined phase difference Δ which is substantially less than π , receiving terminals for receiving said trains of the so determined different phase, a pair of carrier current suppressing balanced demodulators each having input terminals and output terminals and control terminals, said input terminals of said demodulators being connected to said receiving terminals, a pair of blocking devices having substantial conducting asymmetry and each having input terminals and output terminals and control terminals and each being adapted to pass a relatively large current from its input terminals to its output terminals when direct current of a particular characteristic is supplied to its control terminals and to pass only a relatively small current from its input terminals to its output terminals when its control terminals are not so energized, a carrier band pass filter of relatively large time constant, a first connection between the input of said carrier filter and the output terminals of said blocking devices, said first connection comprising first dephasing means inserted in the connection to the output terminals of at least one of said blocking devices for dephasing the output of one of said blocking devices relative to the output of the other blocking device by a substantial angle which is substantially less than π , and equal to said determined phase difference of said two alternating currents applied to said receiving terminals, second connections between the output of said carrier filter and control terminals of said demodulators, said second connections comprising second dephasing means inserted in the lead to the control terminals of at least one said demodulator for dephasing the control current applied to the control terminals of one said demodulator with reference to the control current applied to the control terminals of the other said demodulator by a substantial determined constant phase difference angle which is substantially less than π direct current output connections for said receiver connected in parallel to the output connections of said demodulators, and control connections from the output terminals in parallel of said demodulators to the control terminals in parallel of said blocking devices, the lead of said control connections to the control terminals of a first one of said blocking de-

vices comprising a first asymmetrical conductor element, and the lead of said control connections to the control terminals of the other said blocking device comprising a second asymmetrical conductor element which is poled oppositely to said first conductor element, said control connections and said asymmetrical conductor elements being so arranged that one and only one of said blocking devices at a time is selectively unblocked to pass a relatively large current according to the polarity of the direct current output of said demodulators, whereby the output of said demodulators consists of successive direct current signal elements of both polarities as determined by the phase of the received alternating current signal trains and the phase of the current applied to the input of said carrier filter is substantially constant and the amplitude of said output of said demodulators is independent of the amplitude of said received alternating current signal trains.

3. A receiver according to claim 2, said determined phase difference of said two alternating currents applied to said receiving terminals and of said first and second dephasing means, being substantially equal to

$$\frac{\pi}{2}$$

4. In a receiver for receiving and reconverting into direct current signal elements of successively opposite polarity, a transmitted alternating current signal consisting of successive short trains of two alternating currents of the same frequency but having a determined phase difference which is substantially

$$\frac{\pi}{2}$$

receiving terminals for receiving said trains of the so determined different phase, a carrier current suppressing demodulator having input terminals and output terminals and control terminals, said input terminals of said demodulator being connected to said receiving terminals, a pair of blocking devices having substantial conducting asymmetry and each having input terminals and output terminals and control terminals, and each being adapted to pass a relatively large current from its input terminals to its output terminals when direct current of a particular polarity is applied to its control terminals and to pass only a relatively small current from its input terminals to its output terminals when direct current of opposite polarity is applied to its control terminals or when its control terminals are not energized, said two blocking devices being poled to pass relatively large currents upon application of opposite polarities to their respective control terminals, a carrier band pass filter of relatively large time constant, connections between the input of said carrier filter and the output terminals of said blocking devices, the connection from a first one of said blocking devices to said carrier filter comprising first dephasing means adapted to introduce a phase displacement of

$$\frac{\pi}{4}$$

70 between its input and its output, the connection from a second one of said blocking devices to said carrier filter comprising second dephasing means adapted to introduce a phase displacement of

$$\frac{3\pi}{4}$$

19

between its input and its output, the output of said carrier filter being connected to the control terminals of said demodulator, direct current output connections for said receiver connected to the output terminals of said demodulator, and control connections from the output terminals of said demodulator to the control terminals of said blocking devices, said control connections and the poling of said blocking devices being such that one and only one of said blocking devices at a time is selectively unblocked to pass a relatively large current according to the polarity of the direct current output of said demodulator, whereby the output of said demodulator consists of successive direct current signal elements of both polarities as uniquely determined by the phase of the received alternating current signal trains and the phase of the current applied to the input of said carrier filter is substantially constant and

5

20

the amplitude of said output is independent of the amplitude of said alternating current signal trains.
